UNITED STATES PATENT OFFICE

HAROLD O. PETERSON, OF RIVERHEAD, NEW YORK, ASSIGNOR TO RADIO CORPORATION OF AMERICA, A CORPORATION OF DELAWARE

SHIELDING FOR HIGH FREQUENCY APPARATUS

Application filed December 21, 1928. Serial No. 327,562.

This invention relates to shielding for high frequency apparatus, and more particularly to the shielding of short wave radio equipment.

5 When very high frequencies are dealt with considerable precaution must be taken to carefully shield the apparatus and circuits employed. Not only must the individual resonant circuits be carefully shielded, but the 10 leads interconnecting these circuits also must be shielded. Because of the high reactance which even a straight piece of conductor offers to very high frequency energy, and to reduce natural capacitive coupling, it is desirable 15 able to keep the leads as short as possible. Tubes especially designed for high frequency work, as for example the screen grid tube, are ordinarily arranged with the control electrode terminal at one end of the tube, and the 20 anode terminal at the other end of the tube. Advantage may be taken of this to convey energy from one stage to another, when intercoupled by a tube, or to couple a shielded resonant input circuit and a shielded resonant 25 output circuit with the tube, by permitting the tube itself to pass through a partition, and then coupling the input circuit in one of the compartments to the control electrode terminal of the tube projecting within that compartment, and the output circuit to the anode 30 terminal within its compartment.

An arrangement with horizontal partitions requires the various stages of the receiver to be located one above another, instead of along side of one another, as is more customarily the case, while sloping partitions are wasteful of space. According to my invention I use the tube as a coupling means, and I attain or even improve on the compactness of the usual arrangement having imperforate vertical partitions by arranging the tube so that it passes through a vertical partition. The tube is preferably kept in a nearly upright position, but with sufficient slant 45 to bring the control electrode terminal within one compartment and the anode terminal within the adjacent compartment.

It has been found desirable, when working with the high frequencies in question, to 50 shield the tube, as well as the leads and reso-

nant circuits. In fact, even when employing a screen grid tube it is well to augment the shielding action of the screen grid by a shield completely surrounding the tube. In order to provide for this I employ a vertical conductive partition having a cylindrical conductive shield extending therethrough at a slant, so that a tube positioned within the shield, while shielded thereby, has its opposite ends accessible on opposite sides of the 55 partition. Of course, the shielding, including the cylindrical shield, is ordinarily grounded, and, if a screen grid tube is employed, the screen grid is connected directly to the shield, at least with respect to radio 60 frequency energy.

The invention is described more in detail in the following specification, which is accompanied by a drawing in which Figure 1 is a section through an amplifier, showing the arrangement of the tubes, while Figure 2 is a wiring diagram of the arrangement shown in Figure 1.

Referring to Figure 1, it will be seen that there is a conductive shielding container 2, 75 which is divided into a plurality of compartments by vertical conductive partitions, such as 4 and 6. The electron emission tubes 8 and 10 are provided with control electrode terminals 12 and 14 at one end, and anode terminals 16 and 18 at the other end. The tubes are passed through the partitions 4 and 6, so that the terminals 12 and 16, and 14 and 18, are on opposite sides of the partitions. The tubes should preferably be kept as nearly upright as possible in order to conserve space, and also in order to cause minimum bending stress on the tube cathode.

The tubes 8 and 10 are surrounded by cylindrical conductive shields 20 and 22. These 90 pass through the partitions 4 and 6, as shown, and are preferably affixed integrally thereto by soldering around the surface of the cylindrical shield.

The invention is applicable to various 95 forms of apparatus, but Figures 1 and 2 exemplify a simple two stage amplifier, to which energy is fed by a lead 24, and coupled through a coil 26 to a resonant input circuit 28. An astatic shield 30 may be provided be- 100

tween the primary and secondary coils in order to prevent capacitive coupling therebetween. One side of the resonant input circuit 28 is coupled by the lead 32 to the control electrode terminal 12, while the other side is grounded to the shield with respect to radio frequencies, preferably through a blocking condenser 34, in order to make possible the application of direct bias potential to the control electrode of the tube, as is better indicated in Figure 2. The output energy is taken from the anode terminal 16 to one side of the resonant output circuit 36, the other side of which is connected to the shield through a blocking condenser 38. The output circuit acts also as an input circuit for the next amplifier stage, and for this purpose one side of the resonant circuit 36 is coupled to the control electrode terminal 14 of the next tube, through a blocking condenser 40, in order to keep the anode potential of the tube 8 from the control electrode of the tube 10. The control electrode of the tube 10 may be biased by an external source coupled to the lead 39, which may include a resistance, as shown.

The output of the tube 10 is taken from the anode terminal 18 to one side of the output circuit 48, the other side of which is connected to the shield through a blocking condenser 50. The output of the amplifier is supplied to a utilization circuit through a lead 52.

Referring more particularly to Figure 2, it will be seen that electron emission tubes employed are preferably screen grid tubes, and it will be seen that the screen grids are connected to the shield, with respect to radio frequencies, preferably through blocking condensers 54 and 56, in order to make it possible to apply a desired direct potential to the screen grids. It will also be noticed in Figure 2 that the cathodes of the tubes are connected to the shields with respect to radio frequency energy, thereby completing the control electrode to cathode and the anode to cathode circuits of the tubes. Cathode heating current, control electrode bias potential, and anode polarizing potential, are all fed through appropriate leads, connected between the blocking condensers and the appropriate electrodes, and preferably provided with radio frequency chokes, as is indicated in Figure 2.

55 I claim:

In combination, a shielding container including a vertical metallic partition dividing it into a plurality of shielded compartments, said vertical partition having a cylindrical conductive shield extending therethrough at a slant, said cylindrical conductive shield being integrally connected to said vertical partition, an electron emission tube comprising an anode, a cathode, a control electrode, an anode terminal at one end of the

tube, and a control electrode terminal at the other end of the tube, said tube being placed at an angle relative to the vertical and positioned within said cylindrical shield so that the control electrode terminal is in one compartment while the anode terminal is in the adjacent compartment, an input circuit situated in the first compartment, an output circuit situated in the second compartment, means coupling the input circuit to the control electrode terminal, and means coupling the output circuit to the anode terminal.
